INSECT ELECTROCUTING TRAP

Steward L. Stafford, Boxford, Mass.
(3510 NW. 33rd Place, Gainesville, Fla. 32601)

Filed Dec. 9, 1970, Ser. No. 26,370

Term of patent 14 years

Int. Cl. D22—06

U.S. Cl. D22—19

Fig. 1.

Fig. 2.

FIG. 1 is a front view of an insect electrocuting trap embodying my new design; and

FIG. 2 is a side view from either side of the insect electrocuting trap of FIG. 1.

I claim:

The ornamental design for an insect electrocuting trap, as shown and described.
